UNITED STATES PATENT OFFICE.

GUSTAVE E. VILLARET, OF LEONIA, NEW JERSEY, ASSIGNOR TO WILLIAM R. NOE & SONS, OF NEW YORK, N. Y., A COPARTNERSHIP.

DESIGN FOR A PLATE FOR LIGHTING FIXTURES.

Application filed May 21, 1925. Serial No. 13,523. Term of patent 7 years.

To all whom it may concern:

Be it known that I, GUSTAVE E. VILLARET, a citizen of the United States, residing at Leonia, in the county of Bergen and State of New Jersey, have invented a new, original, and ornamental Design for Plate for Lighting Fixtures, of which the following is a specification, reference being had to the accompanying drawing, forming part thereof.

Fig. 1 is an edge view.

Fig. 2 is a top plan view showing my new design.

I claim—

The ornamental design for a plate for lighting fixtures, as shown.

GUSTAVE E. VILLARET.
